Inventor:
Jacob M. Enders,
by Alexander S. Gant.
His Attorney.

UNITED STATES PATENT OFFICE.

JACOB M. ENDERS, OF SCHENECTADY, NEW YORK, ASSIGNOR TO GENERAL ELECTRIC COMPANY, A CORPORATION OF NEW YORK.

VARIABLE CONDENSER.

Application filed September 22, 1923. Serial No. 664,330.

My invention relates to the construction of electrostatic devices such as variable condensers comprising two sets of plates in which the plates of one set are interleaved with those of the other set and are mounted to be moved relatively thereto. The object of my invention is to provide an improved construction of the condenser plates whereby accurate spacing of the plates of each set is assured without the use of separate spacing members.

The invention will be better understood by reference to the accompanying specification and drawing and its scope will be pointed out in the appended claims. In the drawing, Figure 1 is a view partly in section of a condenser involving my invention; Fig. 2 is a horizontal sectional view taken on line 2-2 of Fig. 1; and Fig. 3 is a detail drawn to a larger scale.

The condenser comprising my invention is built up of two sets of substantially semi-circular plates, a stationary set 1 and a movable set 2, the plates of the two sets being interleaved and relatively movable without contact. The plates comprising each set are identical. Each stationary plate has three openings 3 of a size to receive the securing means to be described later. As shown more clearly in Fig. 3, the plate is provided at each opening with two pairs of integral ears or boss elements. Ears 4 and 5 of one pair are arranged diametrically opposite each other and project upwardly on the same side of the plate. Ears 6 and 7 of the other pair are also arranged diametrically opposite each other but project downwardly on the opposite side of the plate and are displaced 90 degrees from the first mentioned pair. This ear formation may be conveniently made by punching an aperture in the plate, from this aperture, lancing the plate in four directions and drawing alternately up and down the adjacent ears thus formed. If greater accuracy is desired in the spacing of the plates, the plates may then be finished to give a definite and predetermined height to the ears, the height of the ears being one half the space between plates. A series of plates thus formed may be stacked to form a unit by inverting each alternate plate so that the boss elements of one plate engage the boss elements of the adjacent plate and thus space the plates.

For convenience in handling a set of stationary plates a sleeve 8 may be passed through the opening 3, and the unit thus formed firmly secured to a pair of insulation plates 9 and 10 by bolts 11 and nuts 12, a suitable spacing washer 13 being shown between the upper insulation plate 9 and the head of the sleeve 8.

The plates comprising the movable set are each provided with a single opening 14 and with integral spacing ears like those of the stationary plates just described. They are stacked up in the same manner, each alternate plate being inverted, and the unit firmly clamped on a spindle 15 between a sleeve 16 and a nut 17. The spindle is shown having the usual knob 18 and dial 19.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States, is,—

1. In an electric condenser a plurality of metal plates, each formed with a portion of the plate folded to form a boss on one side of the plate and with a different portion of the plate folded to form a boss on the opposite side of the plate, said plates being assembled in parallel relation so that the boss of one plate falls in juxtaposition with respect to the boss on the adjacent side of the next plate, whereby a spacing is insured between the plates greater than the height of either adjacent boss between any of the plates.

2. In an electric condenser a plurality of metal plates, each having a boss upon each side thereof, said bosses on each plate being formed by the sections of the plate between two incisions in the plate which cross each other, being folded, one with both its faces projecting to one side of the plate and the other with both its faces projecting to one side, to wit, the opposite side of the plate, and an opening formed in each plate between the folded sections of each plate, said plates being arranged in parallel relation with respect to each other and with the bosses in juxtaposition and in alignment.

3. In an electric condenser a plurality of

2

metal plates, each having a boss upon each side thereof, said bosses on each plate being formed by the sections of the plate between two incisions in the plate which cross each other, being folded, one with both its faces projecting to one side of the plate and the other with both its faces projecting to one side, to wit, the opposite side of the plate, and an opening formed in each plate between the folded sections of each plate, said plates being arranged in parallel relation with respect to each other and with the bosses in juxtaposition and in alignment, and means extending through said openings for binding the plates together in the relation indicated.

4. In an electric condenser, a plurality of metal plates, each plate having an opening and a boss formed about said opening in sections, one section extending transverse the plate on one side and the other section extending transverse the plate on the opposite side, the inner and outer faces of each boss being the original faces of the folded sections, said plates being assembled in parallel relation with the bosses in juxtaposition, and means extending through said opening for clamping said plates together.

In witness whereof, I have hereunto set my hand this 21st day of September, 1923.

JACOB M. ENDERS
